(57) **CLAIM**

The ornamental design for a rifle scope, as shown and described.

DESCRIPTION

FIG. 1 is a perspective view of a rifle scope showing my new design;

FIG. 2 is a front view thereof;

FIG. 3 is a rear view thereof;

FIG. 4 is a top plan view thereof;

FIG. 5 is a bottom plan view thereof;

FIG. 6 is an enlarged view showing a portion defined by 6-6 in FIG. 1; and,

FIG. 7 is an enlarged view showing a portion defined by 7-7 in FIG. 2.

The features shown in broken lines in the drawings depict portions of the article that form no part of the claimed design. The dash-dotted lines in the drawings denote the boundary of the claim and form no part of the claimed design.

1 Claim, 7 Drawing Sheets
